UNITED STATES PATENT OFFICE.

ALFRED H. EXTON, OF CHICAGO HEIGHTS, ILLINOIS, ASSIGNOR TO AMERICAN MANGANESE STEEL COMPANY, OF AUGUSTA, MAINE, A CORPORATION OF MAINE.

SECTIONAL SHOE FOR THE RUNNER-VANES OF CENTRIFUGAL PUMPS.

1,327,812.

Specification of Letters Patent. Patented Jan. 13, 1920.

Application filed June 6, 1919. Serial No. 302,118.

To all whom it may concern:

Be it known that I, ALFRED H. EXTON, a citizen of the United States, and a resident of Chicago Heights, in the county of Cook and State of Illinois, have made and invented certain new and useful Improvements in Sectional Shoes for the Runner-Vanes of Centrifugal Pumps, of which the following is a specification.

- 10 My invention relates to improvements in the runner or rotor of centrifugal pumps, and more particularly to the wearing shoes with which the runner vanes are ordinarily provided.
- 15 The use of protecting shoes upon the runner vanes for centrifugal pumps has now become the general practice due to the abrasive action of the sand and gravel which pass through the pump during the dredging operations. Heretofore it has been necessary to dismantle the pump and remove the rotor or runner in order to renew the shoes after they have become worn. This dismantling of the pump and detachment of the runner 25 from the driving shaft so as to allow it to be removed from the pump shell involves considerable labor and time and has been necessary due to the large size of the wearing shoes, which prevented them from being withdrawn through the suction opening of the runner, and also due to their extreme weight, which prevented them from being easily and conveniently handled.

It is accordingly an object of my invention to provide wearing shoes which may be installed or removed from the runner without requiring the same to be removed from the pump shell or detached from the driving shaft, thus reducing to a minimum the period of shutdown involved due to renewing the wearing shoes of the runner.

A further object is to accomplish the aforementioned ends and at the same time provide a wearing shoe which may be conveniently handled, may be inserted through the suction opening within the runner and installed in place, and at the same time so constructed that that portion of the shoe which wears more rapidly than the remaining portions may be removed and a new section inserted in place, whereby the maximum life and wear are obtained from each particular part of the wearing shoe.

With the above and other objects in view,

my invention consists in the improved runner or rotor for centrifugal pumps illustrated in the accompanying drawing and hereinafter described and particularly claimed, and in such variations and modifications thereof as will be obvious to those skilled in the art to which my invention relates.

In the accompanying drawings:

Figure 1 is a view in side elevation, and partly in section, showing a centrifugal pump having my improved runner shoes installed therein;

Fig. 2 is a sectional view of the runner taken on the line 2-2 of Fig. 1;

Fig. 3 is a view in section taken on the line 3-3 of Fig. 1; and

Fig. 4 is a view in perspective of my improved wearing shoe.

Referring particularly to the several views of the drawing, the centrifugal pump shown is of the conventional type as employed in sand and gravel dredging plants and includes the shell or body portion 4 having the peripheral delivery opening 5 and the suction opening 6. Located within the shell and rotatably mounted upon the shaft 7, is the rotor or runner 8, the same being formed in the customary manner and including the frame or side pieces 9, driving hub 10, and vanes 11, the latter being curved in the usual manner, as more clearly shown in Fig. 1.

Rigidly attached to the vanes 11, either by rivets, bolts, or other suitable means, are the wearing shoes 12, the same being composed of the coplanar and coextensive sections 13-13, the line of division of which extends longitudinally or diametrically of the pump. These sections are provided with the lap joint 14, whereby the same are protected from the abrasive action of the solid material which passes through the pump and assurance is had that the vane 11 is also properly protected.

The number of sections into which each wearing shoe is divided will depend upon the size and character of the pump, ordinarily two sections being sufficient, but in some instances as high as three or four sections may be utilized.

By thus forming the runner shoe or shoes in longitudinal sections, I am able to quickly and conveniently remove the shoe sections

2
after they have become worn, this being accomplished by first removing the securing bolts or rivets 15 and then withdrawing the shoe sections through the suction opening 16 in the pump runner. This operation does not involve or necessitate the removal of the runner from the pump shell, which can only be accomplished by first disengaging the runner from the driving shaft 7. Further, 10 the forming of the shoe in sections allows the same to be more easily and readily handled and transported from place to place, even though the built-up wearing shoe is of considerable size and weight, such, for example, as would be installed in a centrifugal pump of ten or more feet in diameter.

Furthermore, I have found that in certain instances one side of the runner shoe will wear more rapidly than the other portions, 20 which has heretofore caused the discarding of the entire shoe, entailing considerable loss of metal. With my improved shoe, however, those portions or sections of the shoe which have become but little worn during 25 previous use may be re-used with new sections, so that the maximum wearing life for every portion of the shoe is obtained, this feature being of particular importance as the shoes are ordinarily formed of manganese steel, and the scrapping of a shoe which is only partially worn would involve a considerable financial loss.

Having thus described and explained my invention, I claim and desire to secure by 35 Letters Patent:

1. A wearing shoe for a centrifugal pump runner vane, comprising a plurality of longitudinally curved coplanar sections and

means whereby said sections may be remov- 40 ably secured to said vane.

2. A wearing shoe for a centrifugal pump runner vane comprising a plurality of coplanar and coextensive sections and means whereby said sections may be removably secured to said vane. 45

3. A wearing shoe for a vane of a centrifugal pump runner, the latter having a central suction opening, said shoe comprising a plurality of sections secured to said vane, said runner and shoe sections constructed and adapted, so that said shoe sections may be inserted and withdrawn through said suction opening of the runner. 50

4. In an apparatus of the class described, a runner including longitudinally curved 55 vanes and removable wearing shoes secured to said vanes, said wearing shoes formed in sections and held in coplanar relation.

5. In an apparatus of the class described, a runner including longitudinally curved 60 vanes and removable wearing shoes secured to said vanes, said wearing shoes formed in sections and held in coplanar relation, said runner shoe sections constructed and adapted, so that the shoe sections may be inserted 65 and withdrawn through the suction opening of the runner.

Signed at New York, borough of Manhattan, in the county of New York and State of New York, this 4th day of June, A. D. 70 1919.

ALFRED H. EXTON.
